WARREN R. WALKER, OF GREAT KILLS, NEW YORK, ASSIGNOR TO GENERAL ELECTRIC VAPOR LAMP COMPANY, OF HOBOKEN, NEW JERSEY, A CORPORATION OF NEW JERSEY

ELECTRIC SWITCH

Application filed October 31, 1924. Serial No. 746,945.

My present invention relates to electric switches which are positively proof against the admission of gases and fine solid particles to the moving electric parts of the switch and which are especially suited for use in gas houses, coal mines, grain elevators and other such places, where there is danger of ignition of explosive material by electric sparkings in the switching apparatus. The atmosphere of such places, at times, is extremely sensitive to ignition agencies, especially electric sparks.

It is the object of my invention to provide a hermetically sealed electric switch in which no sparking which is exposed to the atmosphere can occur and which furthermore has a gas proof casing which completely and positively excludes the switch from the outer atmosphere. The casing has an operating mechanism connecting with said switch through a gas tight opening in said casing.

It is an object of my invention to provide an electric switch of the liquid flow type, having a sealed container of insulation material, usually glass, for the circuit making and breaking parts thereof, which container is supported on rigidly attached pivotal support members which serve as terminal leads for the switch and which is surrounded by a gas tight casing, the pivots of said support members being provided with spring washers for keeping the support members in constant electric contact at their pivotal connections and having a handle or operating member connected with said switch or its support members co-axially with said pivots through a gas tight packing or stuffing box in said casing. Conductor leads are run through said casing to the pivots from the outside. These leads are provided with gas sealing means at their points of passage through said casing.

It is also an object of my invention to provide an electric switch which in its operation has long life and which has over a greatly extended period of time no parts which can wear out to result in sparking at such worn places and which has positive means for keeping moving parts in electrical contact, and constantly under pressure

against each other to maintain a non-sparking contact therebetween.

It is a further object of my invention to provide an electric switch having a gas tight covering or casing and positively actuated operating means extending through said casing between which and the casing there is maintained a permanent gas tight joint.

Other objects of my invention will appear from the specification and drawings.

In the drawings:

Fig. 1 is a vertical cross-sectional view, through the switch casing, along the line 1—1, Fig. 2, showing the switch parts end elevation.

Fig. 2 is a vertical cross-sectional view of the switch casing, along the line 2—2, Fig. 1, and showing the switch parts in front elevation.

In the drawings the base 10 supports the block 11 of insulating material which in turn supports the spring clips 14 and 15 by means of the bolts 16 and 17. The rigid metal strips 20 and 21, which are pivoted coaxially at their lower ends to the spring clips 14 and 15, respectively, make contact at their respective upper ends with the respective terminals of the mercury switch tube 24 and serve as support means for said switch. The switch tube 24 is held tightly between two clips, 51 and 50, which are integral parts of the bars 21 and 20, the terminals of the tube being forced between the clips, so that bars 20, 21, block 25, and tube 24 all move as one piece, held rigidly together by means of said insulating block, or platform, 25 which serves as a protecting means for said switch 24 and also serves for holding the electrical connections thereto. The joints between clips 14, 15 and the side bars 20, 21 are made spark-proof by means of spring washers 6, inserted between the pivot heads and nuts and the side bars.

Circuit continuity is thus ensured in all angular positions of the bars 20, 21. To said strip 21 is fixed the member 27 which has a keyhole 28 formed therein at a point which is on the line of the common axis of the pivots of said bars 20 and 21 said keyhole 28 being formed square to admit of the insertion of a correspondingly shaped switch operating le-

ver or key therein. From the character of this connection, it will be seen that the switch parts are positively actuated by the handle 48; i. e., a certain angular movement of the 5 switch tube must correspond to a certain angular movement of the handle. In this way it is always known whether the switch is open or closed. About the switch mechanism and onto said base 10 is mounted the casing 30 by means of the bolts 31, 31. The packing 33 between said casing and said base and the packing 34 between the heads of said bolts 31, 31 and said case 30 serve to make the joints at these points gas tight. The switch leads 37 and 38 connected to bolts 16 and 17 respectively pass through the said base 10 at points within said casing 30 through openings 39, 39. Suitable packing members 40, 40 make a gas tight closure between said openings 39 and the respective leads which pass therethrough. In said casing 30 at a point opposite said key opening 28 is formed an opening 42 in which there is mounted a stuffing box 43 through which the operating key 25 passes when it is positioned in said hole 28 for the operation of the switch. The packing nut 46 serves to press the packing 47 in box 43 about the stem of key 45 for making the 30 slideable joint between said packing and the key stem 45 gas tight.

In the operation and use of the switch of my invention as for instance in a gas house or a grain elevator where there is continued danger of ignition of explosive gases or fine particles of material the switch mechanism is mounted in a suitable position, with the joints between the leads 37 and 38 and the 35 openings 39, 39 in base 10 suitably closed by packing members 40, 40 to make such joints gas tight, the casing 30 mounted on said base 10 about the switch mechanism by means of bolts 31, 31, the joints between the base and the casing and between the casing and bolts being made gas tight by means of packings 40 and 34, 34 respectively and the key 45 is 40 inserted through stuffing box 43 into the opening 28 on the operating member 27 of the switch. The stuffing box is then made gas tight by proper application of pressure on the packing 47 by means of the nut 46. The switch is then operated without danger of 45 ignition to an atmosphere of gas or fine material dust particles by means of the handle 48 on key 45 or other suitable means which is used to tilt the mercury switch 24 into the circuit making or circuit breaking positions as is well known in the art.

Besides applications to the control of circuits operating in dangerously explosive atmospheres my invention has been found to be successful as a safety switch mechanism in the control of track signal systems, where constant exposure to the weather often causes ordinary switch apparatus to fail.

65 My invention provides double hermetical

seals between the spark producing agencies of the switch and the outside, dangerously explosive atmosphere in which the switch is to be used, as a circuit control. First there is the very perfect sealing of the switch tube itself and in addition the protection of its surrounding casing, in case the tube should be destroyed. I also consider the high insulation features of my invention, introduced by the use of the two bars, or blocks 11 and 25, of high grade insulation, an important part of the design. It will be noted block 11 has only a small area of contact with its supporting casing, and that it separates, or spaces, the lead conductors 37, 38 by a good sized gap, and keeps them away from the operating parts of the switch mechanism. Block 25 is mounted at some distance from block 11, and securely holds the side bars 20, 21 rigidly, and at a safe distance apart, at the 70 same time providing for the easy renewal of the switch tube, if that should ever be necessary. These several advantages result, to some extent from the arrangement of block 11, as an insulated shelf, projecting from the 75 back wall of the casing, and the carriage of block 25, by coaxial pivot members, well insulated from each other, at some distance away from its supporting block 11, through the means of rigid side bars, diverging angularly from the support pivots.

What I claim as my invention is:—

1. An electric switch structure comprising a mercury tube switch, a backing member mounted to said switch by means of clip members each of which has a connection with a respective terminal of the tube switch and an extension formed for pivotal support of the switch, pivotal support members for said extensions, a gas tight casing about said switch and its pivotal support, leads connecting with said extensions at their respective pivotal supports and extending through said casing by gas tight passages, and means for operating said switch which extends through said casing by a gas tight packing member.

2. An electric switch structure comprising a mercury tube switch having a sealed envelope, a mounting member for said envelope, straps mounted to said envelope electrically connected to the leads thereof and mounted to said mounting member, said straps having integral extensions thereto formed for pivotal support of the switch, pivotal support members for said extensions, a member mounted to and offset from said extensions and having a portion in axial alignment with said pivotal supports, said axially aligned portion being formed to engage a handle for operating said switch, a gas tight casing about said switch and its pivotal support, and having formed therein an opening for the passage of a handle for engaging said offset portion and a packing gland at said opening.

3. An electric switch structure comprising a mercury tube switch having a sealed envelope, a mounting member for said envelope, straps mounted to said envelope electrically connected to the leads thereof and mounted to said mounting member, said straps having integral extensions thereto formed for pivotal support of the switch, pivotal support members for said extensions, 10 a member mounted to and offset from said extensions and having a portion in axial alignment with said pivotal supports, a gas tight casing about said switch and its pivotal support, handle means extending through 15 said casing by a gas tight packing member and engaging said offset member at said axially aligned part for the actuation of the switch.

4. In a safety spark switch device, for use 20 in explosive gas filled spaces, an hermetically sealed casing inclosure provided with a shelf of insulation material, supported along a single edge of the shelf by a side wall of the casing, and serving as a high insulation platform to pivotally support a block of insulation material, carrying a glass mercury tube switch element, relatively fixed with respect to said block, and actuating means whereby the position of said block on its pivotal support 25 may be changed from the outside of said casing.

5. In a safety spark switch mechanism, for use in explosive gas atmospheres, a fixed switch part comprising an insulation base, 30 and a movable switch part comprising a block of insulation material pivoted thereto by friction washer pivot means, designed to maintain continuity of electrical circuit between said fixed and movable switch parts and terminal clips on said block designed to detachably position a glass mercury tube switch element.

Signed at Hoboken in the county of Hudson and State of New Jersey this 30th day 45 of October, A. D. 1924.

WARREN R. WALKER.
